Primary Examiner — Melanie H Tung*Assistant Examiner* — Fitzgerald Butac(74) *Attorney, Agent, or Firm* — Chun-Ming Shih; HDLS IPR Services(57) **CLAIM**

The ornamental design for a linear actuator, as shown and described.

DESCRIPTION

FIG. 1 is a perspective view of a linear actuator showing my new design;
 FIG. 2 is a front view thereof;
 FIG. 3 is a rear view thereof;
 FIG. 4 is a left side view thereof;
 FIG. 5 is a right side view thereof;
 FIG. 6 is a top view thereof;
 FIG. 7 is a bottom view thereof; and,
 FIG. 8 is second perspective view showing the linear actuator.
